STOVE STRUCTURE

Joseph A. Masonick, Lake Bluff, Ill.

Application January 21, 1939, Serial No. 252,080

8 Claims. (Cl. 126—10)

My invention relates to stove structures designed particularly for household use and for the burning of coal, wood, or other solid fuel.

My invention relates particularly to that type of stove of the down-draft type in which the combustion chamber serves also as a reservoir for comparatively large fuel supplies, and where the combustion or carbureting zone is at the lower end of the fuel stack so that the down-draft through the fuel caused by the stack or chimney pull will carry with it the generated gases and smoke through the combustion zone for complete combustion thereof and the generation of a hot flame flowing through a roundabout flue.

An important object of the invention is to provide a controllable opening adjacent to the bottom of the fuel stack through which paper, kindling or other combustible material may be readily inserted for igniting the fuel and through which opening the air flow may be regulated for rapid combustion of the material and ignition of the fuel at the bottom of the fuel stack.

A further important object is to provide a regulatable air inlet near the combustion zone for regulating the stack or chimney draft and to be particularly serviceable in starting the stack or chimney draft when the stove is to be started so that this created chimney draft may quickly become effective to draw air downwardly through the fuel stack for continued combustion of the fuel after ignition thereof.

A further important object is to provide an arrangement in which an outer frame and an inner frame spaced therefrom form a combustion structure comprising a vertical fuel storage and combustion chamber and a flue passage between the ends thereof and with the upper end of the flue passage communicating with a stack or chimney through which the products of combustion escape.

A further object of the invention is to utilize the space surrounded by the combustion chamber and flue structure as an oven for cooking, baking, or other food preparation.

A further object of this invention is to adapt the stove for space heating by surrounding the combustion structure by an outer shell through which air may circulate for delivery to the room or space to be heated.

Another object is to provide means adapted to be set to cause the stack or chimney draft to effect either downflow or upflow of air through the fuel and combustion chamber.

A further important object is to provide an arrangement in which the flue cross-sectional

area gradually reduces from the combustion zone to the stack inlet in order to assure balanced pull of the stack and complete combustion of the gases in the flue.

The various features enumerated above and other features of my invention are shown incorporated in the structure disclosed on the drawings, in which drawings:

Figure 1 is an elevation of the stove in perspective with parts broken away to more clearly show the construction;

Figure 2 is a plan view with parts broken away; Figure 3 is a section on plane III—III of Figure 2;

Figure 4 is a section on plane IV—IV of Figure 2; and,

Figure 5 is a section on plane V—V of Figure 1.

The stove structure is preferably rectangular and of materially greater length than width. The structure shown is approximately twice as long as it is wide.

The stove comprises an inner or combustion structure, and a surrounding shell or housing spaced at all sides and at the top from the combustion structure for the upward circulation of air to be heated for delivery to the room to be served. The inner or combustion structure comprises an outer rectangular frame preferably constructed of sheet metal. It is formed by the front and rear vertical walls 10 and 11, the vertical side walls 12 and 13, the bottom wall 14, and the removable top or cover wall 15. An inner substantially rectangular frame extends between the front and rear walls 10 and 11 and comprises the top and bottom walls 16 and 17 respectively and the side walls 18 and 19, the walls 16 and 17 being spaced away from the walls 14 and 15 to define lower and upper passageways or flue sections 20 and 21 respectively, and the side wall 18 is spaced away from the side wall 12 to leave a passageway 40 or flue section 22 which joins the flue sections 20 and 21. The side wall 19 is spaced away a greater distance from the wall 13 to provide a reservoir or storage chamber 23 for fuel F, the wall 19 preferably being inclined as shown so that the storage space is of gradually increasing width downwardly to facilitate downward flow of the fuel.

The top wall or cover 15 has an outlet opening 24 surrounded by a collar 25 for receiving a stove-pipe or stack 26 for communication with the upper flue portion or leg 21.

The outer housing or shell comprises front and rear walls 27 and 28, side walls 29 and 30, a bottom wall 31, and a cover structure which is preferably composed of cover sections C, C1 and C2.

The cover structure is displaced from the top or cover wall 15 of the combustion structure to leave space which communicates with the spaces between the side walls of the housing and the combustion structure, the bottom wall 31 having air passageways 32 communicating with the spaces, and the housing cover sections having outlet passageways 33 for the heated air. The housing structure may be supported on suitable feet 34.

The bottom wall 31 is spaced a distance below the bottom wall 14 of the combustion structure and the side wall 13 of the combustion structure may extend downwardly to the housing bottom wall 31. Another vertical wall 35 is interposed between the wall 14 and the wall 31 and the various walls define an ash pit or chamber 36 below the fuel storage space 23. The bottom wall 14 of the combustion structure has the opening 37 therethrough and across this opening extends a grate structure 38 to be interposed between the fuel storage space and the ash pit, the supporting shaft 39 for the grate structure extending outwardly through the front wall of the housing for reception of a crank by which the grate may be shaken. An ash receptacle 39' may be inserted in the ash pit for receiving the ashes. A door 40, supported by the front wall 27 of the housing permits access to the ash pit. The top or cover wall 15 for the combustion structure has the opening 41 above the fuel space 23 through which fuel may be charged into the fuel space, and this passageway may be closed by a door 42 guided by suitable hinge mechanism 43, the door having air passageways 44 adjustable by a slidably damper plate 45 for regulation of the air supply downwardly into the fuel space. When the door is to be opened for charging of fuel into the storage space for the fuel, the housing cover section C2 may be removed or swung aside.

Provision is made so that the upper end of the fuel space 23 may be connected with or disconnected from the upper flue leg or portion 21. As shown, a door or choke plate 46 extends between the front and rear walls 10 and 11 of the combustion structure and is supported on a shaft 47 journaled in these walls and extending forwardly through the housing front wall 27 and there provided with a handle 48, the shaft extending along the top wall 16 of the inner frame of the combustion structure. In the position shown in Figures 3 and 4, the choke plate 46 extends upwardly to shut off communication between the upper flue leg 21 and the upper end of the fuel space 23 so that then the stack draft will cause air to flow downwardly through the door passages 44 into the fuel space and through the fuel, and then through the flue legs 20, 22 and 21 into the stack, in other words, a down-draft through the fuel is created. If the stove plate 46 is swung down as is indicated by the dotted position in Figure 3, the upper flue leg 21 will communicate with the upper end of the fuel chamber and the stack pull will cause updraft of the air through the fuel.

The zone of combustion of fuel will be at the bottom of the fuel stack, as is indicated by Figure 3, and when the choke door 46 is in its upper position, as shown in Figure 3, the air flowing downwardly through the fuel will carry with it any generated gases and smoke for passage through the combustion zone and complete and clean combustion thereof, the resulting flame and products of combustion then flowing serially through the flue legs and into and out of the

stack, as indicated by the arrows on Figure 3. It will be noted that the flue legs are of decreasing cross-section, the flue 22 being of less cross-section than the lower flue leg 20 and the upper flue leg 21 being of less cross-section than the intermediate flue leg 22. This arrangement will compensate for the diminution of gases and will cause the stack draft to be balanced.

The fuel in the fuel storage space may cake and not flow freely downwardly to follow the combustion, this being particularly true if a soft grade of coal is used. However, when this happens, the combustion zone will work its way upwardly along the fuel stack until the fuel becomes loosened sufficiently to flow downwardly, and combustion and the production of heat is maintained until all of the fuel is consumed. Usually, before the fuel is all consumed, a fresh supply of fuel is charged into the fuel space and if there has been any caking of the fuel, such caking will be broken up when fresh fuel is charged into the fuel space.

To facilitate lighting up or starting of the stove, the front wall 10, above the grate, may be deflected to provide a hopper or inlet passageway 49 through which kindling material may be inserted, the hopper being provided with a lid 50 which may be hinged as indicated at 51 so that the hopper passageway may be closed or left partially open for inflow of air to aid the kindling combustion. The hopper structure is accessible through the opening 52 in the front wall 27 of the outer casing, which opening may be provided with a door 53.

During the kindling operation, the choke plate 46 may be opened and the air passages 44 in the door 42 closed by the damper plate, so that there will be updraft through the kindling fire directly into the stack. Then after the fire has been fully kindled and the fuel space 23 is filled with fuel, the choke plate 46 is raised and the air passages 44 opened for the establishment of down-draft thru the fuel by the stack pull and flow of the products of combustion through the flue legs 20, 22 and 21 into the stack.

After the fuel space has been filled with fuel, the stack draft or pull may not pick up sufficiently rapidly owing to the resistance of the air flow through the fuel mass. In order to hasten full stack pull, I provide an adjustable air inlet for the lower flue leg 20 adjacent to the combustion zone. This air inlet 54 is through the front wall 27 of the outer housing structure and may be closed by a suitable door 55 having air passageways 56 therethrough adjustable by a damper plate 57. When this air inlet is opened, the stack pull will be correspondingly relieved from the drag of the air flow resistance through the fuel and this direct air flow through the flues will entrain heat from the combustion zone so that the stack is rapidly heated and its draft or pull rapidly built up. The air inlet 54 may then be closed or the damper plate adjusted for air flow to regulate the stack pull at the combustion zone for thus regulating the combustion and heat output. The draft may be further regulated by adjustment of the air passageway 44 in the door 42 at the top of the fuel chamber, and the desired degree of combustion performance and heat generation can be adjusted and governed to a nicety. With the air flow properly adjusted and applied, there will be clean and complete combustion of the gases, the smoke and the fuel, and there will be very little ash. Whatever ash there be will be comparatively fine and will drop down thru the

grate into the receptacle 39' and there will be little requirement for operation of the grate.

Air flow through the kindling hopper or passageway 49 may also be used for effecting rapid starting or firing up of the stove. When the fuel space has been filled after the kindling operation, the lid 50 may be opened for inflow of air through the passageway 49 and there will then be only a small volume of fuel between this air inlet and the lower flue 20 so that the stack draft may build up rapidly. If it does not build up sufficiently rapidly, the air inlet 54 may be used. After the furnace has been fully started, the lid 50 is closed and then substantially all of the air will flow downwardly through the fuel pile and through the flues into the stack under control of air flow through the air inlet 54 and the fuel chamber air-inlet 44.

The space surrounded by the walls 16, 17, 18 and 19 of the inner frame of the combustion structure may be utilized as an oven for baking, cooking or other food preparation. As best shown in Figure 4, the walls of this oven-forming space are extended through the front wall 10 of the combustion structure and through an opening in the front wall 27 of the outer casing or housing where the walls are flanged to form a seat 58 for a door 59 for opening and closing the open space. The oven is surrounded by the fuel storage and combustion space and the flues and is adequately heated for any cooking or baking purposes. When less heat is required in the oven, the choke plate 46 may be swung down for up-draft operation so that the oven will be heated more strongly from the top when the material to be prepared requires top heat. If the oven is not used for cooking or baking purposes, the door 59 may be opened so that the heat is utilized for heating the room in which the stove is located.

The space 60 below the lower wall 14 of the combustion structure and adjacent to the ash pit may be utilized for storage of utensils or as a warming chamber and may be closed by suitable doors 61.

The top wall or cover 15 of the combustion structure may also be provided with an opening 62 over which kettles or other utensils may be set for cooking or other food preparation purposes. During such use of the stove, the section C1 of the housing top may be removed. The opening 62 also serves as a means through which tools may be applied for cleaning out of the flues. When the opening 62 is not used, it may be closed by a lid 63.

As the lower corner of the oven chamber frame is adjacent to the combustion zone and may therefore become highly heated, I preferably provide a lining 64 of metal or refractory material in this corner to draw heat from the sheet metal wall and prevent burning thereof by the intense heat.

My improved stove is especially adaptable and desirable for household use as it can be used for both cooking purposes and for heating by circulated hot air. The entire and complete combustion of the gases, smoke and fuel gives an exceptionally high combustion efficiency with small cost of fueling. The stove is constructed in greater part of sheet metal and can therefore be economically manufactured.

I have shown a practical embodiment of the various features of my invention, but I do not desire to be limited to the exact construction and arrangement shown and described, as changes

and modifications may be made without departing from the scope of the invention.

I claim as my invention:

1. In a stove structure of the class described, a combustion structure comprising an outer rectangular frame and an inner rectangular frame, said frames being spaced to define a fuel storage and combustion chamber at one side, upper and lower flues extending from the top and bottom respectively of said chamber, and a flue connecting the ends of said upper and lower flues, a stack communicating with the upper flue, a grate at the bottom of said chamber and an air inlet for the top thereof, and means controlling the connection of the upper end of said chamber through said upper flue whereby the stack flow may create either down draft or up draft through said chamber.

2. A stove comprising a combustion structure formed by an outer rectangular frame and an inner substantially rectangular frame, said frames being spaced apart to define a vertical fuel storage and combustion chamber at one end thereof, and a fuel passageway comprising a lower flue leg, an upper flue leg, and an end flue leg, a stack communicating with the upper flue leg, a grate at the bottom of said chamber, means providing an inlet to said chamber adjacent to the grate for the introduction of kindling material for starting the stove and for creating a combustion zone at the bottom of the fuel in the chamber, the stack pull causing the products of combustion to flow serially through the flue legs into the stack, means providing a controllable air inlet to the lower flue leg adjacent to the combustion zone for control of the stack pull.

3. A stove of the class described comprising a combustion structure formed by an outer rectangular frame and an inner rectangular frame spaced from each other to provide a vertical fuel storage and combustion chamber at one side and a continuous flue passageway comprising a lower portion, a side portion and an upper portion, a stack communicating with the upper portion of the flue passageway, a grate below said chamber, means for controlling air flow into the top of said chamber, means for insertion of kindling material into the bottom of said chamber above said grate, means for controlling the connection of the upper end of said chamber with the upper portion of said flue passageway for creation by the stack pull of either down-draft or up-draft in said chamber, and a controllable air inlet for the lower portion of the flue passageway adjacent to the combustion zone in said chamber.

4. A stove comprising a combustion structure formed of an outer rectangular frame and an inner rectangular frame spaced apart to define a vertical fuel storage and combustion chamber at one side and a flue passageway communicating with the bottom of said chamber and extending around the inner frame, a stack communicating with the upper part of said flue passageway, adjustable means for regulating a flow of air directly into said chamber, adjustable means for regulating a flow of air into said flue passageway adjacent said chamber, adjustable means for regulating a flow of air into the top of said chamber, means associated with said adjustable means for regulating air flow for controlling the connection of the upper end of said chamber with the upper part of the flue passageway for creation by the stack pull of either down or up-draft in said chamber, an enclosing housing for said combustion structure hav-

- 5 ing its walls spaced away therefrom to provide
passageways for the upward flow of air to be
heated, the upper wall of said housing having
outlets for the heated air, the space enclosed
by the walls of said inner frame forming an oven
for cooking, baking or the like, the walls of
said inner frame extending through the front
wall of said housing and a door on said housing
front wall for closure of said oven space.
- 10 5. A stove comprising a vertical fuel storage
and combustion chamber, a grate at the bottom
of said chamber, a flue extending laterally away
from the lower end of said chamber, then upwardly
and then back towards the top of said chamber,
15 a stack communicating with the upper end of
the flue, a plurality of means for regulating the
supply of combustion air to said chamber, some
of said means being part of and some adjacent
to said chamber, means for connecting the top
20 of said chamber with the upper end of the flue
or for disconnecting it therefrom for creation by
the stack pull of either up or down draft in
said chamber, walls cooperating with the flue
walls to define an oven for cooking or baking,
25 an enclosing housing for said combustion chamber
and flue having passageways therethrough
for the upward circulation of air to be heated,
and a door on said housing for said oven.
- 30 6. A stove comprising a combustion structure
formed by an outer rectangular frame and an
inner substantially rectangular frame, said
frames being spaced apart to define a vertical
fuel storage and combustion chamber at one
35 end thereof, a flue extending laterally away from
the bottom of said chamber, then upwardly and
then back to the top of said chamber, a stack
communicating with the upper end of said flue,
a grate at the bottom of said chamber, a regu-
40 latable draft inlet at the upper end of said
chamber, a regulatable draft inlet at the end
of the laterally extending flue adjacent said
chamber, a hinged hopper providing an inlet
to said chamber adjacent said grate for the
45 introduction of kindling material for starting the
stove and for creating a combustion zone at the
bottom of the fuel in said chamber, said hopper
adapted to form a portion of the outer frame in
flush relation therewith when closed and to
50 provide a passageway and an adjustable draft
inlet to said chamber when open, and a deflecting
damper for connecting the top of said chamber
with the upper end of the flue and associated
with said draft inlets for creating a regulated
up or down draft in said chamber, the space
surrounded by said chamber and said flue forming
an oven for cooking or baking, and a door
for said oven.
- 5 7. A stove structure of the class described, a
combustion structure comprising an outer rec-
tangular frame and an inner rectangular frame,
said frames being spaced to define a fuel storage
and combustion chamber at one side, upper and
10 lower flues extending from the top and bottom
respectively of said chamber, a flue connecting
the ends of said upper and lower flues, a stack
communicating with said upper flue, a grate at
the bottom of said chamber, an ash pit below
15 said chamber, said grate dividing said chamber
and said ash pit, a plurality of adjustable inlets
for regulating the supply of combustion air to
said chamber, said inlets positioned to direct flows
of air adjacent the ends of and at substantially
20 the center of said chamber as desired, and a
hinged damper in said upper flue between said
stack and said chamber associated with the flow
of air from said inlets for creating a regulated
up draft through said chamber when said damper
25 is in an open position and for creating a regu-
lated down draft through said chamber when
said damper is in a closed position.
8. A stove structure of the class described, a
combustion structure comprising an outer rec-
tangular frame and an inner rectangular frame,
said frames being spaced to define a fuel storage
and combustion chamber at one side, upper and
30 lower flues extending from the top and bottom
respectively of said chamber, a flue con-
necting the ends of said upper and lower flues,
a stack communicating with said upper flue, a
grate at the bottom of said chamber, an ash
35 pit below said chamber, said grate dividing said
chamber and said ash pit, an adjustable draft
inlet at the end of the laterally extending flue
adjacent said chamber, an adjustable draft in-
let to said chamber adjacent said grate, and a
40 deflecting damper connecting the top of said
chamber with the upper end of the flue, said
damper when in a closed position and either of
said draft inlets in open position creating an
up draft through a portion of said fuel next to
45 said combustion chamber whereby the starting
of a fire is facilitated.
